LUGGAGE LOCK

David Damast, 22-14 40th Ave.,
Long Island City, N.Y. 11101

Filed Sept. 14, 1966, Ser. No. 3,855

Term of patent 3½ years

(Cl. D50—7)

FIG. 1 is an exploded perspective view of a luggage lock embodying my new design,

FIG. 2 is a front assembled view thereof,

FIG. 3 is a front assembled view with the catch inverted,

FIG. 4 is a top plan view of the assembled parts shown in FIG. 2, and

FIG. 5 is a side elevational view of the assembly shown in FIG. 2.

I claim:

The ornamental design for a luggage lock, substantially as shown.
